PORTABLE SECTIONAL CONVEYER

Morris J. Andrade, East Orange, N. J., assignor to
 Robins Conveying Belt Company, Passaic, N. J.,
 a corporation of New Jersey

Application January 11, 1935, Serial No. 1,285

5 Claims. (Cl. 198—204)

This invention relates to portable sectional conveyers, more particularly such conveyers for use in mining operations.

The principal object of my invention is to provide a portable sectional conveyer embodying a succession of conveyer belt supporting units of simple and efficient construction which can be readily assembled and disassembled as the room or the runway of the mine or working conditions may require, which units as and when they are being installed readily adapt themselves to the varying grades of the floor of the room or runway.

With this and other objects in view my invention comprises novel features of construction and organization which in a preferred form or forms will be hereinafter fully described, and the scope of the invention then expressed in the appended claims.

In the drawings—

Fig. 1 is a side elevation of the head section of a portable sectional conveyer embodying a form of my invention for use in a room of a mine, showing a portion of the rails which couple the head section to the connecting section of the apparatus.

Fig. 2 is a plan of the structure shown in Fig. 1.

Fig. 3 is a side elevation of the connecting section and the coupling rails as continued from Fig. 1, showing a portion of the succeeding extension section.

Fig. 4 is a plan of the structure shown in Fig. 3.

Fig. 5 is a side elevation of a plurality of extension sections and the tail section, a portion of the first or left hand extension section being represented as a continuation of the portion shown in Fig. 3.

Fig. 6 is a plan of the tail section.

Figs. 7 and 8 are transverse vertical sections through the tail section, as on the lines 7—7 and 8—8, respectively, of Fig. 5.

Fig. 9 is a transverse vertical section through the head section, as on the line 9—9 of Fig. 1.

Fig. 10 is a perspective view of an extension section, and adjuncts.

Fig. 11 is a longitudinal vertical section through the structure shown in Fig. 10, the inclined troughing idlers being omitted.

Fig. 12 is a transverse vertical section through one side of the extension section, adjacent the troughing rolls.

Fig. 13 is a detached perspective view of a standard and the adjacent ends of the rails at

one side of two adjoining extension sections, showing the coupling devices for the rails and the standard, and also a portion of the cross-bar extending from the standard.

Fig. 14 is a side elevation of an extensible or telescopic form of tail section which is used in connection with a "mother" conveyer in the runway of a mine, the extended side bars of the section being partly shown.

Fig. 15 illustrates the remaining portions of said side bars and their mounting on the adjacent extension section.

Fig. 16 is a plan, partially in section, of the structures shown in Figs. 14 and 15.

Fig. 17 is a transverse vertical section through the associated bars of the two sections, as on the line 17—17 of Fig. 16.

Fig. 18 is a transverse section of a modified extension section.

Fig. 19 is a side elevation of the adjoining ends of two extension structures.

Fig. 20 is a section similar to Fig. 18 showing a modification of the belt supporting means.

The conveyer apparatus herein illustrated embodies a head section A; a connecting section B flexibly coupled thereto; a remote tail section C, and a series of extension sections D which are arranged end to end in succeeding order between the connecting and tail sections and which extension sections vary in number in accordance with the length or condition of the room or runway of the mine in which the apparatus is installed.

The head section A comprises a portable rectangular steel framework including parallel upper and lower side rails 20 and 21, respectively, which are downwardly inclined from the front to the rear of the section; spaced transverse bars 22, preferably inverted T-form in cross section, connecting the lower rails; and longitudinal side plates 23 fastened to the adjacent upper and lower rails. These side plates depend throughout the greater part of the length of the head section and are fixed at their lower edges to longitudinally extending skids 24, preferably of angle iron, which facilitate the hauling of the section from place to place. The skids are rigidly connected in parallelism by tie bars 25.

The bars 22, and also the side plates adjacent the ends of the bars, are provided with suitably disposed bearing brackets 26 and 27, respectively, for the shafts of inclined troughing idlers 28 which are adapted to support the upper run of the conveyer belt 29. Each of the bars 22 is also provided on its forward face with bearing bracket

ets 30 for the shaft of a horizontal idler 31, the periphery of which idler extends slightly above the upper edge of the bar so as to support the longitudinal middle portion of the traveling belt 5 and thus prevent its abrasive contact with the edge of the bar.

A sheet metal decking 32, which extends throughout the length of the frame structure and below the idlers 28, 31, is supported on the 10 lower side rails 21, and by the cross bars 22, which decking reinforces the structure and also receives any spillage from the overlying belt run.

The front ends of the side plates 23 and the upper rails 20 are connected by a reinforcing strip 33 to which are secured suitable bearings 34 for the shaft 35 of the head or drive pulley 36 for the conveyer belt 29, which shaft is operatively connected with and driven from a suitable source of power. In the present instance 20 the shaft 35 is equipped at its respective ends with sprocket wheels 37, either of which may be operatively connected by means of a chain 38 with a sprocket wheel 39 on the shaft 40 of a gear reducer 41 which is associated with an electric motor 42. The motor and reducer are mounted on a common bed plate 43, in order that the drive unit can be readily positioned at either side of the frame structure and operatively connected with one of the sprocket wheels on the shaft 30 of the head pulley 36, thus permitting either side of the conveyer structure to be placed in close relation to a wall of the room or runway of a mine, as working space or conditions of operation may require. A single drive or tandem drive for the 35 conveyer belt may be employed.

The frame structure of the head section is provided adjacent the head pulley 36 with a snub pulley 44 for the conveyer belt, which latter pulley is mounted on a transverse shaft 45 having its bearings 46 on the two side plates. The structure in the form herein illustrated for use in a room of a mine is provided with a similarly mounted bend pulley 47 located at the rear of and below the pulley 44, and also with a take-up pulley 48 spaced rearwardly from the latter pulley.

The conveyer belt 29 is trained about the pulleys 48 and 47, as seen in Figs. 1 and 2, in order that when the pulley 48 is bodily moved toward 50 or from the pulley 47 the tension of the belt can be regulated or the slack of the belt taken up as need may require in the operation of the apparatus. In the present instance the bearings for the shaft 49 of the take-up pulley are formed in 55 side blocks 50 which are guided in parallel longitudinally extending rails 51 fixed to the respective side plates 23 of the head section. The guide blocks may be operated by any suitable devices. In the present instance these blocks are connected by cables 52 with a suitable winch 53 conveniently supported on a skeleton frame extending from the rear of the structure, which frame comprises parallel angle bars 54 affixed to the side plates and supported at their outer ends by 60 connecting pieces 55 fastened thereto and to the rearward ends of the adjacent skids 24.

The winch, in the form illustrated, includes a transverse shaft 56 which is journaled in bearings 57 on the frame bars 54 and carries at its ends 70 winding drums 58 for the take-up cables 52, which cables are guided by sheaves 59 supported in suitably-disposed brackets 60 on the side plates.

The shaft 56 is geared with an adjacent 75 parallel shaft 61 which is also journaled in bear-

ings 618 on the frame bars 54 and is adapted to receive at either end, as desired, an actuating crank 62. A suitably disposed back-stop or dog 63 co-operates with a ratchet wheel 64 on the shaft 61.

The connecting section B consists of a portable steel framework including longitudinally extending skids 65; spaced standards 66 fastened thereto; cross-bars 67, similar to the bars 22, connecting the opposite standards, and parallel angle 10 rails 68 fixed to the tops of the standards at the respective sides of the structure. These rails are slightly inclined downwardly from the forward to the rearward end of the structure.

Each of the cross-bars and also the adjacent 15 standards at the ends of the bar, are provided with lugs or brackets 26 and 21, respectively, which similarly to the corresponding parts of the head section, afford bearings for the shafts of inclined troughing idlers 28 adapted to support 20 the upper run of the conveyer belt. Each bar is also similarly provided on its forward face with bearing brackets 30 for the shaft of a horizontal idler 31, which supports the middle longitudinal portion of the belt. The standards 66 are slotted 25 at suitable intervals to provide bearings for idlers 69 for the support of the lower or return run of the conveyer belt.

The connecting section B is spaced a suitable 30 distance rearwardly of and in alignment with the head section A and is joined thereto by means of parallel rails 680 which are flexibly coupled to the respective sections as will presently appear so as to constitute, in effect, continuations of the respective rails 20 and 68 of the two sections. 35

When the sections are thus assembled and coupled the idlers 28 and 31 of the associated sections are in proper relative position to support and guide the upper run of the conveyer belt.

A laterally flanged sheet metal decking 70, which extends throughout the length of the connecting structure and below the idlers thereof so as to receive spillage from the belt 29, is supported by the standards 66. The space between the 45 deckings 32 and 70 is bridged by two laterally disposed sheet metal spillage pans 71 which rest at their ends upon and are detachably supported by the rear and forward cross-bars 22 and 67 of the head and connecting sections, respectively. 50

The coupling means hereinbefore referred to for the ends of the rails 680 comprises, in the form illustrated, two depending gravity hooks 72 which are pivoted, as at 73, to the vertical side members of the respective rails 680, the lower edge of each 55 of such members being formed with a notch 74 in front of the hook. The side plates 23 of the head section A and the forward standards 66 of the connecting section B are provided with projecting headed studs 75 which are positioned for 60 entry in the respective notches 74 when the sections and the rails 680 are assembled and also to receive the lower or engaging ends of the hooks which automatically gravitate to locking position on the studs. 65

The opposing ends of the respective rails are oppositely-beveled, as at 76, to permit the relative flexure of the sections about the axes of the respective studs when the sections are coupled together, as stated.

By the described form of coupling it will be seen that the adjoining sections can be securely coupled with ease and facility, and that the coupled sections have capacity for free vertical pivotal movement at their junctures, thus permit- 70 75

ting relative up and down movement of the sections to adapt them to the varying grades or irregularities of the mine floor. To uncouple the sections it is merely necessary to unlatch the hooks from the studs and disengage the notched rails from the latter.

Each of the rearward standards 66 of the connecting section B is provided with a headed stud 75 adapted to co-act with complementary coupling means in connection with the parallel side rails 77 of an adjoining extension section D now to be described.

The extension section comprises a pair of standards 78 generally similar in construction to the standards 66, but provided with two adjacent studs 75. The standards 78 are also connected by a similar cross-bar 67 which carries the supporting idlers 28 and 31 for the upper run of the belt.

The standards 78 are spaced a suitable distance from the rear standards 66 of the connecting section, and the rails 77 are supported at their respective ends on the spaced standards, which ends are notched, as at 14, to engage the proximate studs 75, and are provided with pivoted gravity hooks 72 positioned to engage the studs and flexibly lock the ends of the rails 77 to the respective standards. The standards 78, similarly to the standards 66, are provided with bearing slots to receive the shaft of a return idler 69.

The structural arrangement just described constitutes a self-contained cradle mounting the idlers 28, 31, and 69 at the respective ends of the extension section and for the support of the rail members 77 which connect the cradle with the corresponding cradle of a succeeding extension section.

The rails 77 of each extension section carry an intermediate cradle mounting a set of idlers 28 and 31 only, which cradle, with its idlers can be readily inserted in or removed from the main cradle, as occasion may require.

The intermediate cradle comprises a transverse L-bar 79 having at its ends flanged hangers, whereof the flanges 80 are adapted to rest upon and be supported by the respective side rails, which rails are provided with lateral lugs 81 that are welded thereto and disposed to embrace the legs 82 of the respective hangers and thereby retain the intermediate cradle in rigid position.

Laterally disposed spillage pans 83 rest at their ends upon and are detachably supported by the side flanges of the respective L-bars 67 and 79.

Any number of corresponding extension sections may be assembled and endwise coupled together at the adjoining ends of the side rails in the manner hereinbefore described, as the length of the room or runway or conditions of operation may require.

The rails of the rear or final extension section are then flexibly and detachably coupled to the rearward standards 84 of the tail section C by coupling means similar to that previously described for the ends of the side rails, it being noted that the opposing pivoted ends of the rails are shaped to permit their free movement relative to each other as and for the purpose previously mentioned.

In the present instance, the tail section C, which is a portable unitary structure, comprises spaced pairs of standards 84 each pair connected by a transverse L-bar 67. The bar and standards carry idlers 28, 31, and 69 similarly to the bar and standards of the extension section. The standards 84 rise from longitudinally extending

skids 85 and are fixedly connected at their upper ends by means of parallel side rails 86.

The rear of the tail section embodies a sheet metal housing 87 which is supported by the skids 85 and the rails 86, and which housing contains the tail pulley 88 for the conveyer belt 29, the shaft 89 of such pulley being mounted in bearings in the sides of the housing.

Adjacent one side of the housing is a cylindrical casing 90 which is affixed to the proximate side rail 86 and is provided with suitable supporting feet 91 adapted to rest on the mine floor.

Rotatably mounted within and concentrically of the casing at one side of the latter, is a disc 92 which carries a circular series of spaced radial vanes 93 in close proximity to the inner peripheral wall of the casing, and which disc is fast on a stud shaft 94 having its bearings in the adjacent side wall of the casing. This shaft is provided with a sprocket wheel 95 which is connected by a chain 96 with a similar wheel 97 on an extension of the tail pulley shaft 89, whereby when the pulley is rotated by the frictional action of the traveling conveyer belt thereon during the operation of the apparatus, the desired motion is transmitted to the disc and its vanes.

These vanes in their rotation receive and carry up any dirt or other spillage that may be delivered into the bottom of the casing from the lower run of the conveyer belt, through a lower opening 98 in the inner side wall of the casing, as hereinafter mentioned, and then discharge such material upon an inclined chute 99 leading through an upper opening 100 in said wall to the upper run of the conveyer. A suitably disposed stationary segmental guard wall 101 within the casing extends from the lower inlet to the upper outlet opening and in close proximity to the path of the vanes, in order to maintain the contained material in the path of the vanes and ensure its rapid delivery thereby to the chute.

In the present instance an angularly disposed scraper 102 is arranged above the lower or return run of the conveyer belt 29 in advance of the tail pulley 88 so as to intercept the dirt or spillage on such run and deflect it toward and into a throat structure 103 which is secured to the wall of the casing at the mouth of the inlet opening 98 to the latter, which spillage, entering the casing through the opening, is carried up by the rotating vanes 93 and delivered thereby to the chute 99 as previously described.

The scraper is supported at one end by an angle piece 104 secured to the adjacent standard 84, and at the other end is secured to the throat structure. A laterally flanged sheet metal decking 105, which is arranged directly below the idlers and fastened to the standards 84, receives spillage from the upper run of the belt and also reinforces the tail structure.

The side rails 86 of the structure support metal aprons 106 which overlie the adjacent sides and the rear portion of the upper run of the belt so as to ensure the proper loading of the belt.

It is to be noted that when the tail section of the installation is uncoupled the belt take-up mechanism in the head section permits of the gradual advancement of the tail section in the room of the mine in order to follow the face cut as it progresses, which take-up mechanism has sufficient range of movement to enable the tail section to be advanced the depth of several full cuts without the necessity of inserting an additional section of belt or an extension frame section in the conveyer structure.

- It will be seen that my invention provides a simple and efficient sectional conveyer structure in which corresponding extension frame sections for the belt are employed, that is to say, the structural elements of the respective sections are symmetrical and interchangeable, thus facilitating the selection and assembly of the parts in the mine; for example, any troughing idler pulley assembly, including its standards, can be placed at the rearward end of the first extension section or at either end of any of the intervening extension sections, and any side rail may be placed on either side of any of the extension sections.
- It will also be seen that the main cradle of each extension section is a complete self-contained unit mounting its troughing and return idlers, and that the secondary cradle is a complete self-contained unit mounting the intermediate troughing idlers. Further that there are no small loose pieces, such as bolts or pins, required for assembling the structural elements of the respective sections, and that each individual part of the organization, except the drive, connecting and tail sections, is light enough to be handled by one man, and since those sections are mounted on skids they can be severally hauled about to facilitate their movement from one room or runway to another.
- In Figs. 14 to 17, inclusive, of the drawings, I have shown an alternative construction and arrangement of an extensible tail section for use in connection with a "mother" conveyer installed in the runway of a mine, which conveyer functions as an effective receiving unit for one or more room conveyers, delivering material either to cars or to a conveying system for transporting the material out of the mine.
- In the construction illustrated the tail section, instead of being pivotally coupled directly to the adjacent extension section D as hereinbefore described, is provided with two forwardly extending angle bars 107 which are rigidly fixed to the side standards 84 of the tail section and are slidably or telescopically mounted on the vertical members 108 of angular bars whereof the horizontal members 108 constitute rails for the support of a flat conveyer belt 29. The members 109 are preferably provided with liners 110 of non-corrosive metal upon which the edges of the belt are supported, and the standards 78 of the extension sections afford bearings for transverse anti-friction rollers 111 upon which the belt is supported at spaced intervals.
- The tail section just described when it is located in the desired rearward position within the runway, is secured to a stanchion 112 detachably supported between the floor and the roof of the mine, preferably by means of a suitable coupling device, such as the threaded rods and turnbuckle 113 shown in Fig. 14. In addition, the tail section is or may be firmly held in place by a pair of screw pressure bars or jacks interposed between the roof of the mine and brackets fixed on the respective sides of the tail section. One of the jacks and the bracket therefor are shown at 114 and 115, respectively, (Fig. 14).
- In the case of a "mother" conveyer, wherein the extensible tail construction just described is employed, the take up mechanism on the head section is dispensed with, since as new rooms are opened up the tail section can be moved back in the runway, an extension section or sections can be inserted between the main conveyer line and the tail section, and the belt can be corre-

spondingly extended by the addition of a suitable length, or lengths, of belt material, in order to extend the conveyer the necessary distance to receive material from a new room conveyer.

The improved conveyer constructions hereinbefore described are low—about two and a half feet in height—which is a desideratum in underground or mine conveyers, and when such constructions are installed they readily adapt themselves to the varying grades or irregularities of the room or runway floor.

In Figs. 18 and 19 of the drawings I have shown a modified construction wherein the side rails 77 for the respective extension sections are constituted by flanged sheet metal plates having inwardly and downwardly inclined apron-like extensions 116 which are effective to support and turn up the longitudinal edges of the conveyer belt 29, thereby imparting a trough form to the belt without the employment of troughing idlers. The adjoining ends of the side rails formed by the plates have affixed thereto downwardly extended flange pieces 117 and 118 which are spaced to receive and embrace the upper end of the standard 78, thus laterally supporting the respective plates. The flanges 117 are provided in their lower edges with notches 14 to receive the studs 75 on the standard and are also provided with gravity hooks 72 positioned to engage the studs as in the first described construction.

In this modification the standards of each pair are connected by parallel tie-bars 670, and an elongated horizontal idler 310 is located between the bars so as to support the bottom of the belt. The shaft of the idler has its bearings in the standards and the periphery of the idler 310 extends slightly above and below the tie bars. Directly under this idler is a parallel return idler 690 for the lower run of the belt, the shaft of which latter idler also has its bearings in the standards. Since the idler 310 is positioned directly above and transversely of the belt, such idler serves to prevent the return run of the traveling belt from whipping and scraping against the opposing lower edges of the tie bars.

In Fig. 20 I have shown another slightly modified construction wherein the pair of parallel side rails 77 are constituted by the flanged longitudinal edge portions of a single sheet metal plate which is longitudinally depressed throughout its length to provide a unitary troughing support for the upper run of the belt 29. In this construction the ends of the flanged portions of adjoining plates are locked to the standards as in the other modified construction, the like parts of the coupling devices being correspondingly identified.

It is to be understood that my invention is not limited to the exemplifying constructions herein disclosed, as structural changes may be made within the fair spirit of the invention and the scope of the appended claims.

I claim—

1. A portable sectional conveyer comprising an endless conveyer belt, a plurality of separable belt-supporting structures arranged in succeeding order, said structures including separable standards having studs adjacent their upper ends, and also including side rails having adjacent their respective ends downwardly opening notches for pivotal engagement with the studs, and locking hooks mounted on the rails to swing below the studs of the respective standards.

2. In a portable sectional conveyer, an endless conveyer belt, a belt-supporting structure com-

5 prising a main cradle including standards, cross-bars connecting said standards in pairs, and side rails detachably supported at their ends on said standards, a supplemental cradle including a cross-bar, outwardly extending flanges on the cradle resting on the rails for suspending the cradle from the respective rails, and means for 10 flexibly and detachably coupling the ends of the respective rails to the associated standards.

10 3. In a portable sectional conveyer, an endless conveyer belt, a belt-supporting structure comprising a main cradle including standards, cross-bars connecting said standards in pairs, and side rails detachably supported on said standards, 15 a supplemental cradle including a cross-bar, outwardly extending flanges on the cradle resting on the rails for suspending the cradle from the respective rails, belt-supporting idlers mounted on the cross-bars of the respective cradles, and 20 means for flexibly and detachably coupling the ends of the respective rails to the associated standards.

4. A portable conveyer comprising an endless belt conveyer, a succession of belt-supporting structures including side rails provided adjacent their ends with downwardly opening stud receiving notches, stud-supporting members adjacent the ends of the respective rails, studs on said members arranged to be pivotally engaged by the notches of the respective rails, and locking hooks pivotally mounted on said rails for engagement with and disengagement from the under sides of said studs, as desired. 10

5. A portable conveyer comprising an endless conveyer belt, succeeding belt-supporting sections including side rails provided adjacent their ends with downwardly opening stud-receiving notches, spaced pairs of standards, studs on said standards arranged to be pivotally engaged with the stud-receiving notches of the respective rails, and gravity actuated locking means on said rails for engagement with the under sides of said studs 15 for locking the rails against upward movement. 20

MORRIS J. ANDRADA.
